UNITED STATES PATENT OFFICE

2,663,067

APPARATUS FOR WINDING

Robert H. Roughsedge, Ramsey, and Arthur Meder, Carlstadt, N. J., assignors to Celanese Corporation of America, New York, N. Y., a corporation of Delaware

Application May 19, 1949, Serial No. 94,118

5 Claims. (Cl. 28—38)

1

This invention relates to textile apparatus and relates more particularly to warpers.

As a preliminary step in the weaving and knitting of textile fabrics, at least a portion of the yarns which go into said fabrics are drawn from a plurality of yarn packages and are wound in substantially parallel relation onto a positively driven warp beam mounted in a warper. During this operation, it is essential that the winding on the warp beam remain level since, if any high spots develop in said winding a larger amount of yarn will be drawn from certain of the yarn packages as compared with others for each revolution of the warp beam. Non-uniformity in the windings during the formation of the warp will result in a corresponding non-uniformity in the let-off of the yarns from the warp beam during the weaving and knitting, with the production of defective woven or knitted fabrics. To assist in maintaining a level winding on the warp beam, it has heretofore been the practice to provide a press roll in the warper, which press roll bears against the winding and serves to flatten out any high spots therein. In order for the press roll to function properly, the pressure which it exerts against the winding on the warp beam must remain substantially constant during the entire warping operation even though the diameter of the winding increases. The mechanisms hitherto employed for urging the press roll against the winding on the warp beam have failed to maintain this constant pressure, particularly at high warping speeds, with the result that defective warps were produced, making it necessary to limit the maximum warping speed.

It is an important object of this invention to provide a warper which will be free from the foregoing and other disadvantages of the prior warpers.

A further object of this invention is the provision of a warper which will produce a level winding.

Other objects of this invention, together with certain details of construction and combinations of parts, will be apparent from the following detailed description and claims.

In accordance with this invention a warper, including a press roll and means for engaging a warp beam, is provided with fluid operated means for urging the press roll against the winding on a warp beam mounted in said warper. We have found that by employing fluid operated means for this purpose, the pressure which the press roll exerts against the winding may be maintained substantially constant even at high

warping speeds and even though the diameter of the winding increases during the warping operation. As a result, more uniform warps may be produced and the speed of warping may be increased above the previous maximum. The warper of this invention is also provided with fluid operated means for loading and unloading warp beams therefrom, whereby this operation may be carried out more rapidly and with greater safety than has hitherto been achieved with the manual or mechanical means employed for this purpose.

A preferred embodiment of this invention is illustrated in the accompanying drawings in which:

Fig. 1 is a top plan view of the warper,

Fig. 2 is a side elevational view on an enlarged scale, of the warper shown in Fig. 1,

Fig. 3 is a diagrammatic view of the fluid operated circuit for urging the press roll against the windings on a warp beam mounted in the warper, and

Fig. 4 is a diagrammatic view of the fluid operated circuit for loading and unloading the warp beams.

Like reference numerals indicate like parts throughout the several views of the drawings.

Referring now to the drawings, the reference numerals 11 and 12 designate warper frame members, each having thereon a bearing member such as bosses 13 and 14 in which shafts 15 and 16 respectively are journaled. Hubs 17 and 18 are mounted on the shaft 15 on opposite sides of the frame member 11 and are joined by webs 19 and 21 to a sleeve 22, which is closed at one end with a plate 23. Similarly, hubs 24 and 25 are mounted on the shaft 16 on opposite sides of the frame member 12 and are joined by webs 26 and 27 to a sleeve 28, which is closed at one end with a plate 29.

A shaft 31, having a hand wheel 32 fastened to one end thereof, is mounted for free rotation in the plate 23 and has its other end in threaded engagement with a core 33 slidably mounted in the sleeve 22. The core 33 has a shaft 34 mounted axially thereof, which shaft 34 is journaled for free rotation in a roller bearing 35. Fastened to the shaft 34 is a plate 36 carrying driving pins 37 which engage flange 38 of a warp beam, indicated generally by reference numeral 39, to drive the same. In addition to the flange 38, the warp beam 39 comprises a flange 41, between which flanges is mounted a barrel 42 upon which a warp 43 is wound.

By rotating the hand wheel 32, the core 33 may

be moved longitudinally of the sleeve 22, carrying the driving pins 37 into and out of engagement with the flange 38. To drive the warp beam 39, a gear 44 is fastened to the shaft 34 adjacent to the plate 36. The gear 44 meshes with a gear 45 that is fastened to one end of the shaft 15 and is driven through a pulley 46 fastened to the other end of the shaft 15 by means of a motor and V-belt drive (not shown). The gear 45 is wider than the gear 44 so as to keep said gears fully in mesh as the core 33 is moved longitudinally of the sleeve 22.

The plate 29, which closes the sleeve 28, has a shaft 47 mounted for free rotation therein, which shaft 47 has a handwheel 48 fastened to one end thereof and has its other end in threaded engagement with a core 49 that is slidably mounted in the sleeve 28. A shaft 51 journaled for free rotation in bearings 52 and 53 is mounted axially of the core 49 and has a plug 54 fastened to the end thereof. By operating the handwheel 48, the plug 54 may be brought into engagement with the flange 41 of the warp beam 39 for rotation therewith.

To permit the warp beam 39 to be stopped quickly, there is provided a brake assembly indicated generally by reference numeral 55. The brake assembly 55 comprises a brake drum 56 fastened to the plug 54 for rotation therewith, and expandable brake shoes 57 carried by a stationary plate 58 fastened to the core 49. By expanding the brake shoes 57 into contact with the brake drum 56, a braking force will be imposed upon the warp beam 39 to stop the same.

To raise and lower the warp beam 39, there is provided a fluid operated cylinder 59, one end of which is pivotally fastened to a bracket 61 mounted on the frame member 12. The fluid operated cylinder 59 has a shaft 62 extending therefrom, which shaft is fastened by means of a pin 63 to the lower end of a crank arm 64, the upper end of which is fastened to the hub 24. As the shaft 62 is moved back and forth by the fluid operated cylinder 59, the crank arm 64 will rotate the hub 24 about the shaft 16, raising or lowering the sleeve 28 and the plug 54 carried thereby. The rotation of the hub 24 is also transmitted through the hub 25 and a gear segment 65 fastened thereto, to a gear 66 keyed to a shaft 67, which is journaled for rotation in bosses 68 and 69 on the frame members 11 and 12, respectively. As the shaft 61 rotates, its motion is transmitted through a gear 71 keyed thereto to a gear segment 72 fastened to the hub 18, rotating said hub about the shaft 15, raising and lowering the sleeve 22 and the driving pins 37 carried thereby. The motion of the plug 54 and driving pins 37 serves to raise and lower the warp beam 39 engaged therewith. The warp beam 39 is positioned properly at the upper limit of its travel by stops 73 and 74 on the sleeves 22 and 28, which strike the frame members 11 and 12. To hold the warp beam 39 at its uppermost position securely, the stops 73 and 74 are provided with lips 75 and 76, which are engaged by clamps 77 and 78 pivotally mounted on bolts 79 and 81 and provided with clamping screws 82 and 83. The gears 44 and 45 remain in mesh as the warp beam 39 is raised and lowered, since the shaft 15 serves as a common axis for both the gear 45 and the sleeve 22 carrying the gear 44.

Positioned between the flanges 38 and 41 of the warp beam 39 is a press roll 84, which is mounted for free rotation by means of bolts 85

and 86 on brackets 87 and 88 keyed to a shaft 89. The ends of the shaft 89 are fastened in clamps 91 and 92 at the upper ends of crank arms 93 and 94, whose lower ends are pivotally mounted on bolts 95 and 96 extending through bosses 97 and 98 in the frame members 11 and 12. The assembly supporting the press roll 84 is made more rigid by means of a shaft 99 which, like the shaft 89, is fastened in the clamps 91 and 92. The press roll 84 is urged against the warp beam 39 by means of fluid operated cylinders 101 and 102 pivotally fastened to brackets 103 and 104 mounted on the frame members 11 and 12. The fluid operated cylinders 101 and 102 are provided with shafts 105 and 106 extending therefrom, which shafts are pivotally fastened to the crank arms 93 and 94 through blocks 107 and 108.

When the rotation of the warp beam 39 is stopped by the brake assembly 55, it is necessary to stop the rotation of the press roll 84 simultaneously therewith, since the continued rotation of the press roll 84 will abrade and damage the yarn. To stop the press roll 84, there is provided a brake assembly, indicated generally by reference numeral 109. The brake assembly 109 comprises a brake drum 111 mounted internally of the press roll 84 and expandable brake bands 112 positioned internally of the brake drum 111 and fastened to a stationary plate 113 carried by the bracket 88. A tachometer 114, which measures the speed of the press roll 84, is mounted on the bracket 87 and is driven from said press roll through gears 115 and 116.

To operate the fluid operated cylinders 101 and 102 in order to urge the press roll 84 against the warp beam 39, air or other fluid under pressure is passed from a conduit 117 through a pressure reducing valve 118 into a conduit 119 provided with a pressure gauge 121. From the conduit 119, the air passes through a four-way valve 122 to a conduit 123 and through a pressure relief valve 124, which is set to permit the escape of air from the conduit 123 at a pressure slightly higher than that of the incoming air as determined by the pressure reducing valve 118. The air then flows through throttling valves 125 and 126 into one end of the fluid operated cylinders 101 and 102 and acts on pistons 127 and 128 therein to urge said pistons and the shafts 105 and 106 connected thereto forward. As the pistons 127 and 128 move forward, air is forced from the other end of the fluid operated cylinders 101 and 102 into a conduit 129 through throttling valves 131 and 132, which, by controlling the rate of flow of the air from said fluid operated cylinders, limit the maximum speed at which the press roll 84 can be brought into contact with the warp beam 39 to prevent damage thereto. From the conduit 129, the air discharges to the atmosphere through the four-way valve 122. As a winding of increasing diameter builds up on the warp beam 39, the press roll 84 will force the shafts 105 and 106 and the pistons 127 and 128 back into the fluid operated cylinders 101 and 102 increasing the pressure of the air therein. This excess of pressure will be relieved by the escape of air through the pressure relieve valve 124, thereby maintaining a substantially constant pressure on the pistons 127 and 128 and on the press roll 84. To draw the press roll 84 back from the warp beam 39, the four-way valve 122 is turned through a right angle to connect the air-supply conduit 119 to the conduit 129, and to connect the conduit 123 to the atmosphere. Air under pressure will then flow from the con-

duit 119 through the conduit 129 and the throttling valves 131 and 132 into the fluid operated cylinders 101 and 102 at the under side of the pistons 127 and 128. Simultaneously, air will be forced from the other side of the pistons 127 and 128 into the conduit 123 through the throttling valves 125 and 126, and will discharge to the atmosphere through the four-way valve 122 as the press roll 84 moves away from the warp beam 39.

For raising the warp beam 39, air or other fluid under pressure is passed from a conduit 133 through a pressure reducing valve 134 into a conduit 135. From the conduit 135, the air is led by means of a four-way valve 136 into a conduit 137, and after flowing through a throttling valve 138, enters one end of the fluid operated cylinder 59 forcing a piston 139 and the shaft 62 connected thereto forward. Simultaneously, air will exhaust from the other end of the fluid operated cylinder 59 into a conduit 140 through a throttling valve 141, which controls the rate of flow of the air from said fluid operated cylinder to limit the maximum speed of movement of the warp beam 39 to prevent damage thereto. From the conduit 140, the air discharges to the atmosphere through the four-way valve 136. For lowering the warp beam 39, the four-way valve 136 is turned through a right angle to connect the air-supply conduit 135 to the conduit 140, and to connect the conduit 137 to the atmosphere. Air under pressure will then flow from the conduit 135 through the conduit 143 and the throttling valve 141 into the fluid operated cylinder 59 at the underside of the piston 139 forcing said piston and the shaft 62 connected thereto backward. Simultaneously, air will exhaust from the fluid operated cylinder 59 into the conduit 137 through the throttling valve 138 and will discharge to the atmosphere through the four-way valve 136 as the warp beam 39 descends.

In operation, an empty warp beam 39 is positioned between the driving pins 37 and the plug 54, and said driving pins and plug are engaged with the flanges 38 and 41 of said warp beam by rotating the handwheels 32 and 48. Thereafter, fluid pressure is applied to the fluid operated cylinder 59 to raise the warp beam 39 and said beam is locked in the winding position by means of the clamps 77 and 78. The warp 43 is then led from a creel, or other suitable source (not shown), onto the warp beam 39 and the drive started to wind said warp onto the warp beam. Fluid pressure is then applied to the cylinders 101 and 102 to urge the press roll 84 against the winding on the warp beam 39 with a substantially constant pressure, which effectively prevents the development of high spots therein even at warping speeds much higher than those hitherto employed during this operation. As a result more perfect warps may be produced in a substantially shorter period of time. If the winding operation must be stopped at any time because of a broken yarn, or for any other reason, the brake assemblies 55 and 109 are actuated, simultaneously stopping both the warp beam 39 and the press roll 84 preventing abrasion and damage to the yarn. When the winding on the warp beam 39 is complete, the clamps 77 and 78 are unlocked and the warp beam is lowered by means of the fluid operated cylinder 59. The handwheels 32 and 48 are then operated to retract the driving pins 37 and plug 54 from the warp beam 39, and said warp beam is removed, at which time the entire cycle is repeated.

While the means for urging the press roll against a warp beam and the means for raising and lowering the warp beam have been described with particular reference to a warper, they may also be employed in other textile apparatus wherein a warp is wound on a warp beam, and wherein a warp beam is raised and lowered.

It is to be understood that the foregoing detailed description is given merely by way of illustration and that many variations may be made therein without departing from the spirit of our invention.

Having described our invention, what we desire to secure by Letters Patent is:

- 15 1. Textile apparatus wherein the warp of yarns is wound onto a warp beam, comprising means for supporting said warp beam, means including a train of gears and fluid operated means for moving said gears to raise and lower said warp beam supporting means to and from the winding position of said warp beam, means for locking said warp beam in said winding position, a press roll adapted to operate against said warp beam for pressing the yarn windings thereon, and fluid operated means, operatively separate from said means for raising and lowering said warp beam, for moving said press roll toward said warp beam at a predetermined speed and for causing said press roll to effect a continuous and constant pressure on the yarn windings on said warp beam.
- 20 2. Textile apparatus wherein the warp of yarns is wound onto a warp beam, comprising means for supporting said warp beam, means including a train of gears and fluid operated means for moving said gears to raise and lower said warp beam supporting means to and from the winding position of said warp beam, means for locking said warp beam in said winding position, a press roll adapted to operate against said warp beam for pressing the yarn windings thereon, and fluid operated means, operatively separate from said means for raising and lowering said warp beam, for moving said press roll toward said warp beam at a predetermined speed and for causing said press roll to effect a continuous and constant pressure on the yarn windings on said warp beam.
- 25 3. Textile apparatus wherein the warp of yarns is wound onto a warp beam, comprising means for supporting said warp beam, means including a train of gears and fluid operated means for moving said gears to raise and lower said warp beam supporting means to and from the winding position of said warp beam, means for locking said warp beam in said winding position, a press roll adapted to operate against said warp beam for pressing the yarn windings thereon, and fluid operated means, operatively separate from said means for raising and lowering said warp beam, for moving said press roll toward said warp beam at a predetermined speed and for causing said press roll to effect a continuous and constant pressure on the yarn windings on said warp beam.
- 30 4. Textile apparatus wherein the warp of yarns is wound onto a warp beam, comprising means for supporting said warp beam, means including a train of gears and fluid operated means for moving said gears to raise and lower said warp beam supporting means to and from the winding position of said warp beam, means for locking said warp beam in said winding position, a press roll adapted to operate against said warp beam for pressing the yarn windings thereon, and fluid operated means, operatively separate from said means for raising and lowering said warp beam, for moving said press roll toward said warp beam at a predetermined speed and for causing said press roll to effect a continuous and constant pressure on the yarn windings on said warp beam.
- 35 5. Textile apparatus wherein the warp of yarns is wound onto a warp beam, comprising means for supporting said warp beam, means including a train of gears and fluid operated means for moving said gears to raise and lower said warp beam supporting means to and from the winding position of said warp beam, means for locking said warp beam in said winding position, a press roll adapted to operate against said warp beam for pressing the yarn windings thereon, and fluid operated means, operatively separate from said means for raising and lowering said warp beam, for moving said press roll toward said warp beam at a predetermined speed and for causing said press roll to effect a continuous and constant pressure on the yarn windings on said warp beam.
- 40 6. Textile apparatus wherein the warp of yarns is wound onto a warp beam, comprising means for supporting said warp beam, means including a train of gears and fluid operated means for moving said gears to raise and lower said warp beam supporting means to and from the winding position of said warp beam, means for locking said warp beam in said winding position, a press roll adapted to operate against said warp beam for pressing the yarn windings thereon, and fluid operated means, operatively separate from said means for raising and lowering said warp beam, for moving said press roll toward said warp beam at a predetermined speed and for causing said press roll to effect a continuous and constant pressure on the yarn windings on said warp beam.
- 45 7. Textile apparatus wherein the warp of yarns is wound onto a warp beam, comprising means for supporting said warp beam, means including a train of gears and fluid operated means for moving said gears to raise and lower said warp beam supporting means to and from the winding position of said warp beam, means for locking said warp beam in said winding position, a press roll adapted to operate against said warp beam for pressing the yarn windings thereon, and fluid operated means, operatively separate from said means for raising and lowering said warp beam, for moving said press roll toward said warp beam at a predetermined speed and for causing said press roll to effect a continuous and constant pressure on the yarn windings on said warp beam.
- 50 8. Textile apparatus wherein the warp of yarns is wound onto a warp beam, comprising means for supporting said warp beam, means including a train of gears and fluid operated means for moving said gears to raise and lower said warp beam supporting means to and from the winding position of said warp beam, means for locking said warp beam in said winding position, a press roll adapted to operate against said warp beam for pressing the yarn windings thereon, and fluid operated means, operatively separate from said means for raising and lowering said warp beam, for moving said press roll toward said warp beam at a predetermined speed and for causing said press roll to effect a continuous and constant pressure on the yarn windings on said warp beam.
- 55 9. Textile apparatus wherein the warp of yarns is wound onto a warp beam, comprising means for supporting said warp beam, means including a train of gears and fluid operated means for moving said gears to raise and lower said warp beam supporting means to and from the winding position of said warp beam, means for locking said warp beam in said winding position, a press roll adapted to operate against said warp beam for pressing the yarn windings thereon, and fluid operated means, operatively separate from said means for raising and lowering said warp beam, for moving said press roll toward said warp beam at a predetermined speed and for causing said press roll to effect a continuous and constant pressure on the yarn windings on said warp beam.
- 60 10. Textile apparatus wherein the warp of yarns is wound onto a warp beam, comprising means for supporting said warp beam, means including a train of gears and fluid operated means for moving said gears to raise and lower said warp beam supporting means to and from the winding position of said warp beam, means for locking said warp beam in said winding position, a press roll adapted to operate against said warp beam for pressing the yarn windings thereon, and fluid operated means, operatively separate from said means for raising and lowering said warp beam, for moving said press roll toward said warp beam at a predetermined speed and for causing said press roll to effect a continuous and constant pressure on the yarn windings on said warp beam.
- 65 11. Textile apparatus wherein the warp of yarns is wound onto a warp beam, comprising means for supporting said warp beam, means including a train of gears and fluid operated means for moving said gears to raise and lower said warp beam supporting means to and from the winding position of said warp beam, means for locking said warp beam in said winding position, a press roll adapted to operate against said warp beam for pressing the yarn windings thereon, and fluid operated means, operatively separate from said means for raising and lowering said warp beam, for moving said press roll toward said warp beam at a predetermined speed and for causing said press roll to effect a continuous and constant pressure on the yarn windings on said warp beam.
- 70 12. Textile apparatus wherein the warp of yarns is wound onto a warp beam, comprising means for supporting said warp beam, means including a train of gears and fluid operated means for moving said gears to raise and lower said warp beam supporting means to and from the winding position of said warp beam, means for locking said warp beam in said winding position, a press roll adapted to operate against said warp beam for pressing the yarn windings thereon, and fluid operated means, operatively separate from said means for raising and lowering said warp beam, for moving said press roll toward said warp beam at a predetermined speed and for causing said press roll to effect a continuous and constant pressure on the yarn windings on said warp beam.
- 75 13. Textile apparatus wherein the warp of yarns is wound onto a warp beam, comprising means for supporting said warp beam, means including a train of gears and means for moving said gears to raise and lower said warp beam supporting means to and from the winding position of said warp beam, means for locking said warp beam in said winding position, a press roll adapted to operate against said warp beam for pressing the yarn windings thereon, and fluid operated means, operatively separate from said means for raising and lowering said warp beam, for moving said press roll toward said warp beam at a predetermined speed and for causing said press roll to effect a continuous and constant pressure on the yarn windings on said warp beam.

to raise and lower said warp beam supporting means to and from the winding position of said warp beam, means for locking said warp beams in said winding position, a press roll adapted to operate against said warp beam for pressing the 5 yarn windings thereon, and fluid operated means, operatively separate from said means for raising and lowering said warp beam, comprising a cylinder, a piston mounted in said cylinder and operatively connected to the press roll, a source of fluid under pressure, means for conducting said fluid into one end of said cylinder on one side of said piston so that said piston moves in a direction to move the press roll into contact with said warp beam, means for releasing said fluid from said cylinder to maintain its pressure constant as said press roll is forced back by the building up of yarn windings on said warp beam so that said press roll effects a continuous and constant pressure on said warp beam, and means including a valve for simultaneously connecting the compressed end of said cylinder to the atmosphere and connecting the opposite end of said cylinder to said source of fluid pressure to move said press roll away from said warp beam.

5. Textile apparatus wherein the warp of yarns is wound onto a warp beam, comprising means for supporting said warp beam, means including a train of gears and fluid operated means for moving said gears to raise and lower said warp beam supporting means to and from the winding position of said warp beam, means for locking said warp beam in said winding position, a press roll adapted to operate against said warp beam for pressing the yarn windings thereon, and fluid 30 operated means operatively separate from the

means for raising and lowering said warp beam, comprising a cylinder, a piston mounted in said cylinder and operatively connected to the press roll, a source of fluid under pressure, means including a throttle valve for conducting said fluid into one end of said cylinder on one side of said piston so that said piston moves in a direction to move the press roll into contact with said warp beam, means for releasing said fluid from said cylinder to maintain its pressure constant as said press roll is forced back by the building up of yarn windings on said warp beam so that said press roll effects a continuous and constant pressure on said warp beam, means including a valve for simultaneously connecting the compressed end of said cylinder to the atmosphere and connecting the opposite end of said cylinder to said source of fluid pressure to move said press roll away from said warp beam, and brake 20 means operatively connected to said warp beam supporting means and to said press roll for stopping the rotation of said warp beam and said press roll.
